(57) **ABSTRACT**

A topper for a container having an upper surface is presented. The topper includes: a body adapted to engage an upper surface of the container, and a movable perforation platform having at least one protruding perforating element. The perforation platform is pushable with respect to the body from a resting position to a working position wherein the perforating element perforates the upper surface of the container. The perforation platform presents in resting position a first orientation and presents in working position a second orientation, the first and the second orientation differing by an angle of less than 30°. Also, an assembly and a method of using the assembly are presented.

TOPPER FOR A CONTAINER

CROSS REFERENCE TO RELATED APPLICATIONS

The present application is a national phase entry under 35 U.S.C. § 371 of International Application No. PCT/EP2014/079500, filed on Dec. 31, 2014, published in English, which claims priority from PCT Application No. PCT/EP2013/078164 filed Dec. 31, 2013, the disclosures of which are incorporated by reference herein.

FIELD OF THE INVENTION

The invention generally concerns sealed containers, in particular containers for liquids, for example beverages.

More precisely, the invention relates to a topper for such a sealed container.

BACKGROUND OF THE INVENTION

Yogurt is a milk based product which is eaten using a spoon or drunk.

Drinkable yogurts, as well as various beverages, are generally sold in containers such as small plastic bottles comprising a neck, sealed with a lid or a screwed cap. The seal or cap is to be removed by a user to drink the content of the bottle.

However, the operation of removing the lid is generally impractical, as the lid is glued to a flange of the container, and the liquid content may be spilled when removing the lid. This operation can be even more critical if a container has a large opening, for example if the container is a cup.

Instead of removing the lid, it has been proposed to only pierce it so as to drink through the created opening, similarly to how it could be performed with a straw. Therefore, the beverage can be easily drunk everywhere and in any circumstances, including when walking or when having only one free hand.

The Utility Model ES 1079052 describes a flat accessory with a perforation funnel which can be applied to a container for perforating it. A hole in the accessory enables drinking through the opening consequently created within the lid. Such accessory is efficient, but it requires being manually placed on the lid at first, and then carefully handled by the user, which is detrimental for the handiness of the product. Furthermore, the accessory may be lost.

The patent applications JP2004123155 and JP2003327266 disclose two accessories for containers, each presenting a moveable part with a cutting edge. These accessories must securely engage the container before using the edge, which improves their reliability. However such accessories still require inconvenient manual handling. Moreover, these accessories are complex, bulky and expensive.

Besides, all said known perforation accessories may create excessively large openings in the container if handled without the necessary caution, and the beverage may be spilled.

In view of these drawbacks, there is a need for an improved container accessory with is simpler, cheaper, handier, while allowing good control of the perforation.

SUMMARY OF THE INVENTION

The present invention proposes in a first aspect a topper for a container having an upper surface, the topper including:

2

a body adapted to engage an upper surface (10) of the container, and

a movable perforation platform having at least one protruding perforating element, the perforation platform being movable with respect to the body between:

a resting position, and

a working position wherein the perforating element perforates the upper surface of the container,

wherein the perforation platform is held in the resting position by at least one breakable portion connecting the perforation platform to the body.

Preferred but non-limiting features of the present invention are as follows:

the body includes a top part and a skirt, the skirt being adapted to engage the upper surface of the container, and the perforation platform being connected to the top part;

when the skirt engages the upper surface of the container, the skirt defines a inner recess extending between the top part and the upper surface, the perforating element fitting in said inner recess when in resting position; the perforation platform is further connected to the top part though at least one hinge;

the perforation platform is connected to a joint part by a first hinge, and the joint part is connected to the top part by a second hinge;

the hinge is located at a distal end of an arm protruding from the top part in said inner recess;

the perforation platform and the at least one breakable portion are integral to the top part;

the top part is at least partially covered by a sticker at least hiding the perforation platform;

the perforation platform further comprises at least one orifice cooperating with the perforating element when the perforating element perforates the upper surface of the container;

the perforation platform comprises two perforation elements and two corresponding orifices.

The present invention proposes in a second aspect an assembly including a topper according to the first aspect and a container, wherein the topper engages an upper surface of the container.

Preferred but non-limiting features are as follows:

the upper surface of the container comprises a lid sealing the container, the lid being perforated by the perforating element when the perforation tab is in working position;

the at least one breakable portion of the topper is adapted to break when a force sufficient for the perforation element to perforate said lid is applied on the perforation platform, so as to enable the perforation element to perforate the lid;

the container is filled with a liquid, for example edible or drinkable liquid, preferably a beverage, preferably a milk-based liquid composition.

The present invention proposes in a third aspect a method of using the assembly according to the second aspect, the method including steps of:

moving the perforation platform from the resting position to the working position;

pouring the liquid filled in the container through the orifice.

BRIEF DESCRIPTION OF THE DRAWINGS

The above, and other objects, features and advantages of this invention, will be apparent in the following detailed

description which is to be read in connection with the accompanying drawings wherein:

FIGS. 1a-b are schematic views of a transversal section of an assembly of a container and a topper according to a first embodiment the invention in a resting position and a working position;

FIGS. 2a-d are schematic views of a transversal section of an assembly of a container and a topper according to a second embodiment of the invention in a resting position and a working position;

FIGS. 3a-c are views under different angles of embodiments of a topper according to the invention;

FIG. 4 is a view of a perforation platform of an embodiment of a topper according to the invention.

DETAILED DESCRIPTION OF THE INVENTION

With reference to FIGS. 1, 2 and 3, the invention proposes a topper 2 for a container 1 having an upper surface 10.

The container 1 is for example a substantially cylindrical (and/or slightly conical) hollow piece made of glass, carton or plastic, in particular, polystyrene (PS), polypropylene (PP), polyethylene (PE), polylactic acid (PLA). As it will be explained, the upper surface 10 is intended to be perforated. This upper part 10 preferably includes a lid sealing the container 1, the lid being for example made of aluminium, paper, plastic, or an association thereof.

The container 1 may have a drinking glass shape or yogurt cup shape. The container may thus comprise an opening, which is to be covered by the upper surface (10), a bottom, and side walls. The opening and/or the side walls can have, horizontally a square cross section or a square with rounded corners cross section, or round cross section or an oval cross section. The walls might form a cylinder shape or conical shape. The walls (perpendicular to the cross section) may be provided with elements such as stickers or banderolles. Elements such as banderolles can contribute to re-enforcing the mechanical resistance of the container. The largest dimension of the cross section, for example the diameter of the cross section is circular, of the opening is herein referred to as "D" or "width". The height of the walls is herein referred to as "H". In some embodiments $0.5H \leq D \leq H$. In some embodiment $0.5D \leq H \leq D$. In one embodiment the container does not present a neck with a narrowed opening compared to the side walls cross section. In another embodiment the container has a bottle shape with a neck.

The container 1 can be filled with a liquid, preferably a milk-based composition. The liquid in the container 1 can be any liquid, for example an edible or drinkable liquid, often referred to as foods liquids. It can be for example a sauce, a soup or a beverage: herein beverage include waters, juices, sodas, milk-based compositions such as milk, optionally flavored, and fermented milk products, for example yogurt or kefir.

The container may be for example a container of 50 ml (or 50 g), to 1 L (or 1 kg), for example a container of 50 ml (or 50 g) to 80 ml (or 80 g), or 80 ml (or 80 g) to 100 ml (or 100 g), or 100 ml (or 100 g) to 125 ml (or 125 g), or 125 ml (or 125 g) to 150 ml (or 150 g), or 150 ml (or 150 g) to 200 ml (or 200 g), or 250 ml (or 250 g) to 300 ml (or 300 g), or 300 ml (or 300 g) to 500 ml (or 500 g), or 500 ml (or 500 g) to 750 ml (or 750 g), or 750 ml (or 750 g) to 1 L (or 1 kg).

It is to be understood that the skilled person would know how to adapt the topper according to the invention to any container 1 having an upper surface 10.

In the exemplary embodiment represented by figures, the container 1 is 85 mm tall ($H=85$ mm), 65 mm wide ($D=65$ mm).

The topper 2 is for instance a piece crowning the container 1. It can be made of a similar or different plastic material as container 1, for example polystyrene (PS), polypropylene (PP), polyethylene (PE), polylactic acid (PLA). PP is found to present a good flexibility and breakability compromise. In other words, the topper 2 includes a body adapted to engage the upper surface 10 of the container 1, in particular in a secure way.

As it can be seen on FIG. 1a or 2a, the body includes a top part 2a and a skirt 2b, wherein the skirt 2b engages the upper surface 10 of the container 1. The top part 2a can be a flat part, and the skirt 2b can be cylindrically shaped. Thus, a reverse cross-section of the topper 2 is "U"-shaped.

The upper surface 10 is preferably engaged according to its periphery. In other words, by engaging it is meant cooperating with this periphery of this upper surface 10 so as to assemble the container 1 and the topper 2.

Thus, in the example of FIG. 1a or 2a, the skirt 2b includes at least one tab 21 which protrudes from the inner surface of the skirt 2b and extends radially towards the center of the topper 2. This tab 21 cooperates with at least one further tab 11 protruding from the edge of the container 1 (i.e. at the periphery of the upper surface 10), said further tab 11 extending radially toward the exterior of the container 1. When the upper surface 10 of the container 1 engages the topper 2 due to a translation movement of the container 1, the skirt 2b deforms (in particular through an elastic deformation) until the tabs 11 of the container 1 reach beyond the tabs 21 of the skirt 2b, so as to "clip" the topper 2 on the container 1.

When the skirt 2a engages the upper surface 10, the skirt 2b defines an inner recess V (in particular a cylindrical volume) between the top part 2a and the container 1. In the exemplary embodiment, the topper 2 is 12 mm tall, and the inner recess V defined is nearly 8 mm deep.

Perforation Platform

The topper 2 is provided with a movable perforation platform 3 having at least one protruding perforating element 4a, 4b. As represented by FIG. 3a, this perforation platform 3 is connected (directly or not, at it will be explained) to the top part 2a.

The perforation platform 3 includes at least one orifice 5a, 5b, preferably a main orifice 5a and an auxiliary orifice 5b. The main orifice 5a is a drinking orifice, and the auxiliary orifice 5b is a breathing orifice (it allows air entrance within the container 1 to replace the drunk liquid).

The perforation platform 3 is movable with respect to the top part 2a between a resting position and a working position in which the perforating element 4a, 4b perforates the upper surface 10 of the container 1.

When the perforation platform 3 has two orifices 5a, 5b, the perforation platforms 3 has two corresponding perforating elements 4a, 4b. Each perforating element 4a, 4b cooperates with an orifice 5a, 5b so as to create an opening lined up with the orifice 5a, 5b in the upper surface 10 when perforated. In other words, when the perforation platform 3 is in working position, fluidic connection is enabled between the inside and the outside of the container 1 through the perforated upper surface 10 and the perforation platform (via orifices 5a, 5b).

FIG. 3b represents examples of perforating elements 4a, 4b. In particular, both perforating elements 4a and 4b can be sharp pieces of various shapes. In FIG. 3b, the main piercing element 4a (cooperating with the main orifice 5a) is

U-shaped, and the auxiliary piercing element **4b** (cooperating with the auxiliary orifice **5a**) is H-shaped.

On the first embodiment, the resting position is represented on FIG. **1a**, and the working position is represented on FIG. **1b**. On the second embodiment, the resting position is represented on FIG. **2a**, and the working position is represented on FIG. **2d** (FIGS. **2b** and **2c** represents intermediate positions). As it can be seen, the resting position is an “up” position, while the working position is a “down” position.

In these examples, the movement for switching to working position comprises a rotation of the perforation platform **3** according to an axis sensibly parallel to the top part **2a** (by approximately 12° in the exemplary embodiment of FIG. **1a**). At least one hinge **7a** connecting the perforation platform **3** to the top part **2a** (optionally via an arm **20**, as it will be explained later) allows this rotation.

In the exemplary embodiment of FIGS. **1a-1b**, the first hinge **7a** is the only hinge, and therefore the aforementioned rotation is the only one. By contrast, the exemplary embodiment of FIGS. **2a-2d** presents another hinge **7b**. In this embodiment, the top part **2a** is connected to the perforation platform **3** through a joint part **30**. More precisely, the perforation platform **3** is connected to a joint part **30** by the first hinge **7a**, and the joint part **30** is connected to the top part **2a** by a second hinge **7b**. The joint part **30** can be seen as an extension of the perforating platform **3**, which only acts as an articulation enabling the global movement of the perforation platform **3** to be closer to a translation than a rotation.

To this end, the first and the second hinges **7a**, **7b** advantageously present parallel axis. It is to be noted that it is possible to have more than two hinges (and consequently more than one joint part **30**).

As it can be seen in FIG. **2b** the movement for switching to working position begins in this embodiment with only rotation according to the first hinge **7a**, up to the perforating element **4a**, **4b** (and especially the first perforating element **4a**) perforating the upper surface **10**, and a distal end of the perforation platform **3** touching the container **1**. At this point, the joint part **30** and the perforation platform **3** are not lined up, i.e. the hinge **7b** defines an angle inferior to 180° so as to slightly protrude.

If the movement continues, the second hinge **7b** begins to operate (as the distal end of the perforation platform **3** already touches the container **1**, an exclusive rotation according to the first hinge **7a** is no more possible) so as to open the angle between the joint part **30** and the perforation platform **3**. The second perforating element **4b** continues perforating the upper surface **10**. The angle between the joint part **30** and the perforation platform **3** reaches 180° (see FIG. **4c**).

If the movement still continues, the angle between the joint part **30** and the perforation platform **3** exceeds 180° (see FIG. **4d**), i.e. the angle starts to open inwards. Therefore, the perforation platform perfectly fits the shape of the upper surface **10**, which prevents leaks (see below). Furthermore, this position acts as a self-lock because of the over-180° angle, and there is no risk for the perforation platform **3** to unexpectedly go back to resting position.

To trigger the movement, in the examples of FIGS. **1** and **2** a user just has to press the perforation platform **3** with one finger. The user can for example grasp the container **1** with a hand, and press the perforation platform **3** with the thumb. The applied pressure is transmitted to the perforating elements **5a**, **5b**, which consequently perforate the upper surface **10**.

It shall be understood that the present invention is not limited to any kind of action for switching from resting position to working position. Alternatively to pushing, some architectures may propose to translate the perforation platform **3**, or even pulling it (for example if the perforation platform **3** is linked to the top part **2a** by a rotation axis arranged between the first and the second openings **5a**, **5b** (instead of at least one hinge), pulling the rear part of the perforation platform (near the second opening **5b**) leads to the first perforating element **4a** perforating the upper surface **10**).

Breakable Portions

The perforation platform **3** is further held in the resting position by at least one breakable portion **6** connecting the perforation platform **3** to the topper **2**. As represented by FIG. **4**, a plurality (six in the example) of breakable portions **6** may be arranged around the perforation platform **3**. Alternatively, there may be a single breakable portion, in particular located at the distal end of the perforation platform **3**.

A breakable portion is a physical link between the perforation platform **3** and the top part **2a** (for instance a thin plastic thread), which is intended to irreparably break when subjected to a force which is above a given threshold.

It has to be understood that even if the whole topper (as any plastic piece) will ultimately break if subjected to a sufficient force, said threshold is far below the breaking point of the top part **2a**, and sufficiently low for being reachable with the strength of a finger (at the most a few Newtons). In other words, the breakable portions **6** may be seen as “weak points” of the topper **2**: if a stress is applied between the perforation platform **3** and the top part **2a**, the rupture always takes place at the breakable portions **6**, and not in the perforation platform **3** or in the top part **2a**.

The breakable portions **6** have two effects:

in the absence of stresses (i.e. before the user tries to move

(by example by pressing) the perforation platform **3**), the breakable portions **6** keep the perforation platform **3** in the resting position. There is no risk of accidentally switching to working position and unexpectedly perforating the upper surface **10**. In the prior art, the accessory had to be placed on the lid at the very last moment (to avoid unwanted perforation), while in the present invention the topper **2** may be early mounted on the upper surface **10** of the container **1**. To this end, the perforating element **4a**, **4b** advantageously fits in said inner recess **V** when the perforation platform **3** is in resting position. In other words, the inner recess **V** is large enough to contain at least the whole perforation platform **3** (in particular when connected to the top part **2b** via an arm **20**, see after). Therefore, as long as the perforation platform **3** is held in the resting position by the breakable portions **6**, the perforating elements **5a**, **5b** cannot reach the upper surface **11**, while it is protected by the topper **2**.

the “overperforation”, i.e. perforation with an excessive force creating large openings and leaks, is prevented by such topper. Indeed, the breakable portions **6** break as soon as the given threshold is reached. This threshold can be easily controlled by changing the number of breakable portions **6**, their thickness, etc. Therefore, the breakable portions **6** of the topper **2** can be configured so as to break when a force sufficient for the perforating element **4a**, **4b** to perforate the upper part **10** of the container **1** is applied on the perforation platform **3**. In other words, the threshold can be chosen in function of the resistance of the lid, for example in the range

100-150% of the force needed for the perforating element 3 to perforate the upper part 10 of the container 1. Therefore, the lid (the upper part 10) is effectively pierced without being torn.

It can be noted that the perforating platform 3 may be linked to the top part 2a only with breakable portions 6 (i.e. without hinges 7a, 7b nor axis). In such a configuration, the switching movement of the perforation platform 3 is a full translation. When in working position (after the breakable portions 6 are broken), the perforation platform 3 is physically detached from the top part 2a.

Other Improvements of the Topper

Preferably, the perforation platform 3 and the at least one breakable portion 6 are integral to the top part 2a. The limit between the perforation portion 3 and the top part 2a thus forms a "dotted line", the dots of which are the breakable portions 6 spaced apart one from the other. Further, the hinge(s) 7a, 7b is(are) also integral to the top part 2a.

The whole topper 2 can therefore be cast in one piece (for example of polypropylene). The cost and the production time are therefore greatly reduced.

Moreover, the first hinge 7a is preferably located at a distal end of an arm 20 protruding from the top part 2a through said inner recess V, so as to bring this first hinge 7a close to the upper surface 10. Preferably, the distal part of the arm 20 comes to contact the upper surface 10, as represented on FIGS. 1 and 2. Thanks to this arm 20, the perforation platform 3 (and the joint part 30 if there is one) presents an inclination when in the resting position, and becomes horizontal when moved in the working position, therefore fitting the shape of the upper surface 10 (see FIG. 1b), so as to have the orifices 5a, 5b contact the openings created by the perforating elements 4a, 4b. The risk of leaks is therefore greatly reduced.

To further protect the perforation platform 3, the top part 2a may be at least partially covered by a sticker 22 (as represented on FIGS. 2 and 3c), so that the sticker 22 hides at least the perforation platform 3. This sticker 22 prevents any contamination of the orifice 5a. This sticker 22 acts as a tamper-evident element, as it has to be removed or split by the user before moving the perforation platform 3 into working position. To this end, the sticker 22 may be provided with a dotted line (defining a weakness line) in particular following a contour of the perforation platform 3. Thus, the sticker 22 breaks according to the dotted line when pulled by the user, so as to unveil the perforation platform 3, which can be consequently moved for drinking.

In one embodiment, not represented, a protection lid is provided in the inner part of topper to protect the perforation platform, for example to prevent children from being hurt by the perforating element(s). The protection lid can for example be a disc positioned on a shoulder to the skirt. This protection lid is perforated when the perforation platform is moved to the working position.

Assembly

According to a second aspect, the invention proposes an assembly including a topper 2 as previously described, and a container 1 of which an upper surface 10 is engaged with the topper 2. The upper surface 10 of the container 1 is preferably a lid sealing the container 1.

As already explained, there is no more need to mount the topper only right before perforating the container. The assembly can be sold as such, the perforating platform 3 being held by the breakable portions 6 in the resting position. When a user wishes to drink the liquid inside the container, the user just has to apply a force on the perforation

platform 3 up to break the breaking portion 6. It leads to a controlled perforation of the lid 10.

Method

According to a third aspect, the invention proposes a method of using the assembly according to the second aspect of the invention, the method including steps of:

moving (in particular pushing, translating or pulling) the perforation platform 3 from the resting position to the working position (in other words breaking the breakable portions 6);

pouring the liquid filled in the container 1 through the orifice 5a (and the opening created in the upper part 10 of the container 1 by the perforating element 4a).

The invention claimed is:

1. A topper for a container having an upper surface, the topper including:

a body adapted to engage the upper surface of the container, said body having a top part, wherein the body includes a skirt, the skirt being adapted to engage the upper surface of the container and to define an inner recess extending between the top part and the upper surface,

the topper further including a movable perforation platform having at least one protruding perforating element, the perforation platform being connected to the top part, the perforation platform being movable with respect to the body between:

a resting position, the perforating element fitting in the inner recess when in the resting position, and

a working position wherein the perforating element perforates the upper surface of the container,

wherein the perforation platform is held in the resting position by at least one breakable portion linking the perforation platform to the body, said breakable portion being intended to break when a stress is applied to the perforation platform, and

wherein the perforation platform is connected to a joint part by a first hinge, and the joint part is connected to the top part by a second hinge.

2. A topper according to claim 1, wherein the second hinge is located at a distal end of an arm which extends from the top part and which is configured to extend towards the upper surface of the container through said inner recess.

3. A topper according to claim 1, wherein the perforation platform and the at least one breakable portion are integral to the top part.

4. A topper according to claim 1, wherein the top part is at least partially covered by a sticker at least hiding the perforation platform.

5. A topper according to claim 1, wherein the perforation platform further includes at least one orifice cooperating with the perforating element when the perforating element perforates the upper surface of the container.

6. A topper according to claim 5, wherein the perforation platform includes two perforation elements and two corresponding orifices.

7. An assembly including a topper according to claim 1 and a container, wherein the topper engages an upper surface of the container.

8. An assembly according to claim 7, wherein the upper surface of the container comprises a lid sealing the container, the lid being perforated by the perforating element when the perforation tab is in the working position.

9. An assembly according to claim 8, wherein the at least one breakable portion of the topper is adapted to break when a force sufficient for the perforating element to perforate said

lid is applied on the perforation platform, so as to enable the perforation element to perforate the lid.

10. An assembly according to claim 7, wherein the container is filled with a liquid.

11. Method of using the assembly according to claim 10, 5
the method including steps of:

moving the perforation platform from the resting position
to the working position;
pouring the liquid filled in the container through the
orifice. 10
